(57) CLAIM

The ornamental design for a race car mailbox, as shown and described.

DESCRIPTION

FIG. 1 is a top, front, right side perspective view of a race car mailbox embodying my design;

FIG. 2 is a right side elevational view thereof, the left side being a mirror image;

FIG. 3 is a top plan view thereof; the bottom being plain and unornamental;

FIG. 4 is a front elevational view thereof; and,

FIG. 5 is a rear elevational view thereof.
